FLOTATION CELL

Paul L. Wigton, Denver, Colo.

Application October 23, 1940, Serial No. 362,397

3 Claims. (Cl. 209—169)

This invention relates to improvements in flotation cells for the recovery of valuable minerals from their ores. More particularly, the improvement pertains to one or more cells, which are ordinarily used for a preliminary flotation and separation action prior to the classification and final flotation steps.

As ground ore comes from the grinding mill, it may contain, in addition to the ordinary sands, relatively large pieces containing highly valuable metal or mineral, or particles that are too large for flotation. It has been found highly advantageous to effect a preliminary separation between at least some of the floatable size particles, the sands, and the unusually large and/or heavy valuable pieces, before the material is introduced into the classifier.

One reason why this is desirable is that sands and heavy pieces separated in the classifier are ordinarily returned to the grinder for further reduction, but this regrinding is undesirable since it may make valuable constituents more difficult to recover in a later step of the process. However, when one or more cells are used between the grinding mill and the classifier, considerable trouble may be encountered with the heavy sands which are inclined to collect in the bottom of the cell and impede its proper operation.

Therefore, it is an object of this invention to provide a flotation cell of this character that has means for efficiently separating particles that are too large or coarse for ordinary flotation and other heavy pieces from the ground ore.

Another object is the provision in a flotation cell, of a sand outlet, whereby sands that would otherwise accumulate to excess in the bottom of the cell, may be passed out of the cell in an unusually efficient manner.

Other objects and advantages reside in details of design and construction which will be more fully disclosed in the following description and in the drawing wherein like parts have been similarly designated and in which:

Figure 1 is a front elevation, partially in section, of a flotation cell that embodies the present inventive concept; and

Figure 2 is a sectional plan view taken along the line 2—2 of Figure 1.

In order to disclose an operative reduction to practice of this invention, the accompanying drawings which are made a part hereof, will be described in some particularity. However, this drawing and description which discloses a typical example, should not be construed to express or to imply any limitation to the inven-

tion, the scope of which is, in reality, measured by the appended claims.

In the drawing, reference character 5 denotes a single flotation cell having a forwardly extending lip 6 over which a rotary skimmer 7 removes the froth in the usual manner.

An impeller 8 is carried at the lower end of a column 9, which in turn is driven through the intermediary of a pulley 10 by means of a prime mover or other source of power not shown.

At a side of the cell 5 is an adjustable overflow weir 12 over which pulp from the cell 5 flows into discharge compartment 13, which is provided at the bottom with a mineral cone 14, which in turn has means such as a plug 15, for optionally opening and closing its bottom portion.

A discharge outlet 16 is provided in the discharge compartment 13, and means such as one or more pipes 17, are provided for introducing an upwardly-directed stream of water under pressure, into the cone 14 for purposes that will be hereinafter set forth.

One or more tubes 18 are open at their lower ends within the cell 5 adjacent the impeller 8 and positioned radially outward from the impeller, and these tubes 18 open at their upper ends into the interior of discharge compartment 13 below weir 12 and preferably below discharge outlet 16, but somewhat above cone 14 and hydraulic inlet 17.

Under some circumstances, it may be preferable to position the sand outlet tube or tubes as indicated in dotted lines at 18a. Furthermore, the discharge outlet 16 may, under some circumstances, be positioned at a higher elevation with reference to the rest of the structure, than shown in Figure 1, in which case the upper end of the tubes 18 or 18a preferably would be positioned higher than shown to maintain some what the same relationship with the discharge outlet 16.

Operation

In use, pulp or ground ore from the grinding mill is introduced into the cell 5 after the usual manner as well understood by those skilled in the art. As the impeller 8 rotates, froth will be formed which will trap some of the finer mineral particles and this will be skimmed over the lip 6.

Some of the heavier sands and particles will rise in the cell and flow over weir 12 into discharge compartment 13, due to the pumping and agitating action of the impeller.

In the discharge compartment 13, which pro-

vides a stilling and settling zone, the larger and heavier pieces will tend to fall by gravity into the cone 14, particularly pieces which are high in specific gravity.

In order to prevent the cone 14 from filling and clogging with too much sand and other particles not particularly rich in mineral content, an upward component of movement is introduced in cone 14 by discharging water under pressure through hydraulic pipe or pipes 17. This hydraulic action will tend to lift unwanted sands and particles and discharge them through 16, whereas the heavier particles will descend in cone 14 in spite of the upward influence of the hydraulic jets, from where they may be removed and recovered through clean-out 15.

As hereinbefore stated, some of the sands, i. e., the coarsely ground particles of ore, will tend to accumulate in the bottom of the cell 5, particularly in the corners thereof, from where the accumulation will tend to build inwardly toward the impeller. This excess accumulation of sand obviously would be undesirable and would impede the general function of the cell and its impeller in their aerating, agitating and pumping actions.

The tube or tubes 18 or 18a each has its lower end open adjacent the impeller in a direction to receive some of the sands as they are rotated with the pulp in the cell due to rotation of the impeller. These particles of sand will enter the lower open ends of the tube or tubes 18 or 18a and due to the momentum and centrifugal force acting upon them, they will rise through said tubes and be delivered into discharge compartment 13, where they will be acted upon by the upward hydraulic force therein so that their heaviest pieces will settle to the bottom of cone 14 and other particles will pass through discharge 16, which ordinarily would be in conductive communication with the classifier.

Thus is provided a flotation cell in which a preliminary separation is effected between different particles of ground ore; particularly, the heavy pieces are separated and saved from the deleterious effect of regrinding, and the sands are efficiently conducted from the cell in order to prevent excess accumulation therein.

The weir 12 may be adjusted according to circumstances to maintain the optimum depth or head of pulp within the cell 5, and due to the particular combination of the sand outlet tubes 18 and 18a and the hydraulic stilling and separating means 13-14-15-16-17, the pulp or ground ore is passed rapidly through the cell without clogging or interruption of operation of the cell or its impeller, and at the same time large, heavy and highly mineralized pieces are efficiently separated and recovered.

The definite cooperation between the said outlet and the hydraulic separating and discharge

means effects a new and highly desirable result in the art of mineral separation. New advantages are gained and none of the ordinary functions of the flotation cell or its impeller are sacrificed.

It will be understood that the term "pulp" as used herein, refers to ground ore carried in a liquid medium such as water, together with flotation reagents that are well known to those skilled in the flotation art.

Hydraulic jets as indicated at 17, may be one, two or more, and there may be provided one, two or any desired number of tubes 18 or 18a.

The term "sands" is intended to mean ground ore. Due to the particular combination of components and their cooperative functions, applicant prefers to call this a hydrocell.

The patentable improvement is thought to be well defined in the following claims.

What I claim is:

1. In a flotation cell having a closed bottom and inclusive of a rotary impeller and an overflow weir, the improvement which comprises a discharge compartment having a mineral cone at its bottom and having a discharge outlet at its side, said compartment being in receiving communication with the overflow weir, means for introducing an upwardly directed flow of fluid under pressure into the mineral cone, and a sand relief tube open to the interior of the cell adjacent its bottom and open to the interior of the discharge compartment above said cone and below said outlet and below said overflow weir.

2. In a flotation cell having a closed bottom and inclusive of a rotary impeller and an overflow weir, the improvement which comprises a discharge compartment having a mineral cone at its bottom and having a discharge outlet, said compartment being in receiving communication with the overflow weir, means for introducing an upwardly directed flow of fluid under pressure into the mineral cone, and a sand relief tube open to the interior of the cell adjacent its bottom and open to the interior of the discharge compartment above said cone and below said overflow weir.

3. In a flotation cell inclusive of a rotary impeller and an overflow weir, the improvement which comprises a discharge compartment in receiving communication with said weir and having a mineral cone at its bottom and having a discharge outlet at its side, means for introducing an upwardly directed flow of fluid under pressure into the mineral cone, and a sand relief tube extending into the interior of the cell and open thereto adjacent the periphery of said impeller in the zone of centrifugal influence thereof, said sand relief tube being also open to the interior of the discharge compartment above said mineral cone.
